CLAIM

The ornamental design for a dental flosser, as shown and described.

DESCRIPTION

FIG. 1 is a front perspective view of a dental flosser showing my new design;

FIG. 2 is another front perspective view, shown in a position of use;

FIG. 3 is a front view of the dental flosser of FIG. 1;

FIG. 4 is a back view of the dental flosser of FIG. 1;

FIG. 5 is a left side view of the dental flosser of FIG. 1;

FIG. 6 is a right side view of the dental flosser of FIG. 1;

FIG. 7 is a top view of the dental flosser of FIG. 1; and,

FIG. 8 is a bottom view of the dental flosser.

The broken lines are shown for the purpose of illustrating portions of the article and form no part of the claim.
